UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

LOOPER MECHANISM FOR SEWING-MACHINES.

1,190,959.

Specification of Letters Patent. Patented July 11, 1916.

Application filed November 10, 1910. Serial No. 591,735.

To all whom it may concern:

Be it known that I, DUDLEY S. SEYMOUR, a citizen of the United States, residing at Oak Park, in the county of Cook, State of Illinois, have invented certain new and useful Improvements in Looper Mechanism for Sewing-Machines, of which the following is a description, reference being had to the accompanying drawing and to the letters 10 and figures of reference marked thereon.

The invention relates to new and useful improvements in sewing machines, and more especially a sewing machine of the chain-stitch type, wherein both the needle and 15 the looper are thread-carrying elements.

An object of the invention is to provide a mechanism for operating the looper, whereby said looper may be driven at a very high speed, without the skipping of stitches, or 20 the breaking of the needle thread.

In driving a looper at high speed, it is very essential that the point of the looper shall move very close to the needle as it enters the needle loop, and at the same time 25 avoid striking the needle. It is also very essential that the needle in passing the looper shall move very close to the looper, in order to pass between the thread of the looper and the body thereof. I have found 30 that by swinging the looper about substantially a vertical axis when said looper is entering the needle loop, and also by swinging the looper about substantially a horizontal axis to give the same a needle-avoiding 35 movement, I am able to secure to a great degree the movements essential to a high speed machine.

A further object of the invention consists in providing mechanism for operating 40 the feed dog directly from the looper support by a connection which is also located directly underneath the feed dog.

These and other objects will in part be 45 obvious, and will in part be hereinafter more fully described.

In the drawings, Figure 1 is a view partly in plan and partly in section, showing the mechanism for operating the looper and feed; Fig. 2 is a view partly in section and 50 partly in end elevation, showing the looper and the feed, and also the needle and presser foot; Fig. 3 is a front elevation with certain parts of the machine removed, showing

the mechanism for operating the needle and looper; Fig. 4 is a perspective view of 55 the looper support; Fig. 5 is a view showing more or less diagrammatically the position of the needle and looper in side elevation and in plan, when the point of the looper is entering the needle loop; Fig. 6 60 is a similar view, showing the looper at the forward end of its stroke; and Fig. 7 is a similar view, showing the looper moved laterally to avoid the needle; Fig. 8 is a detail showing the connection between the 65 end of the feed bar and the looper support.

In the present embodiment of my invention, I have shown a sewing machine consisting of a bed plate 1, an overhanging 70 arm 2, carrying at its forward end a needle head 3, in which reciprocates a needle bar 4, carrying a needle 5. The needle bar is reciprocated by a needle lever 6 pivoted at 7 to the overhanging arm, and connected 75 by a link 8 to a suitable eccentric on the main shaft of the machine. The presser foot 9 is carried by the presser bar 10, which is raised and lowered by a lever 11. These parts are of the usual construction, 80 and form no part of my present invention. The feed dog 12 is carried by a feed bar 13, which is pivoted at its rear end to a feed rocker 14. Said feed rocker is oscillated by a link 15, connected to a rocking lever 16 actuated by an eccentric on the main shaft. The looper 17 is detachably mounted in a looper carrier 18, which is pivoted to swing about a substantially 85 vertical axis. Said looper is preferably 90 formed on the arc of a circle, the center of which is substantially coincident with the center of oscillation of said looper carrier. The looper carrier is mounted on a looper support 19. Said looper support as herein 95 shown, consists of spaced sleeves 20 and 21. The sleeve 21 is connected to a short stud mounted in a bearing 22 formed in a standard projecting from the bed plate. The sleeve 20 is secured to a short shaft extending through a bearing 23, and carrying at its other end an arm 24, which in turn is pivotally connected with the rocking lever 16. This rocking lever is similar in construction to the rocking lever of the Seymour Patent No. 1,124,667, granted January 105

12th, 1915. Projecting laterally from the looper support and at a point intermediate the sleeves 20 and 21 is an arm 25, which is provided with a bearing for the looper carrier 18. The looper carrier 18 at its lower end is provided with a laterally projecting arm 26, carrying a ball stud 27, to which one end of a link 28 is connected. The other end of the link 28 is connected to a ball stud 29 carried by a rock shaft 30. The rock shaft 30 is in turn connected by a link 31, to the needle lever extension 32. These parts are so positioned that when the looper is at the forward end of its stroke, the needle lever extension 32 and the link 31 are substantially in line, which gives a dwell to the stroke of the looper at this time.

The feed bar 13 is raised and lowered by means of a link 33, which is connected at its upper end to the lower part of the laterally projecting arm 25, which supports the looper carrier. The link 33 at its lower end is connected to a downwardly projecting arm 34, which is formed as a part of the feed bar and extends underneath the looper support. The arm 34 is located directly underneath the feed bar 13, and the forward end of the arm is substantially underneath the forward end of the feed bar. The link 33 is substantially a vertical link, and, therefore, the lifting force exerted by the looper support is directly underneath the forward end of the feed dog. This construction, whereby the lift of the feed dog is brought about by a connection directly underneath the same, prevents all chances of tilting of the feed dog laterally and brings the strain directly underneath the feed dog, whereby a very efficient feed action is secured.

In the operation of my machine, the looper carrier 18 swings about its axis, through the action of the connected link 28, and causes the looper to move into and out of the needle loop. The looper support rocks about its axis through the action of the rock lever 16, and causes the looper to move bodily across the needle path, so that the looper will move forward into the needle loop on one side of the needle across the needle path, and be retracted from the needle loop on the other side of the needle path. When the looper is entering the needle loop, the supporting arm 25 is inclined slightly from the horizontal, as shown in Fig. 5, and consequently the axis of the looper carrier is slightly inclined at this time to the vertical. I am able, therefore, to set the needle and the looper, so that the point of the looper will pass very close to the needle as it enters the needle loop, for the reason that as the looper moves forward into the needle loop, the arm 25 is rocked so as to raise the same slightly

through the action of the rock lever 16, and this gives sufficient room for the body of the looper to pass by the needle to the position shown in Fig. 6. I further secure the clearance between the needle and the looper by curving the body of the looper, as clearly shown in Fig. 1. When the looper reaches the forward end of its stroke, the arm 25 is substantially horizontal, as shown in Fig. 6. At this time, the link 31 is substantially in line with the needle lever extension 32, and the looper is given an extended dwell at the forward end of its stroke. During this dwell, however, the looper is moved laterally, so as to be properly positioned for the passing of the needle between the body of the looper and the looper thread. During this lateral swing of the looper, the arm 25 moves to the position shown in Fig. 7, thus carrying the looper to the opposite side of the needle path, as clearly shown in this figure. When the looper is positioned as shown in Fig. 7, the face of the looper adjacent the needle is inclined to the vertical with the upper edge of the looper at some distance from the needle path, and with the lower edge of the looper very close to the needle path. This inclined face of the looper allows the setting of the needle very close to the looper, for the reason that if the needle should be slightly sprung and should strike the inclined face of the looper, it will be quickly brought back to its proper path and pass the looper without breaking the needle. I am thereby able to cause the needle to pass very close to the looper, and said needle will pass between the looper body and looper thread with certainty, thus causing the proper interlocking of the thread.

It will be noted that as the looper swings to the opposite side of the needle path to a position for the needle to pass between the looper thread and the body of the looper, that said looper moves downward and away from the cloth plate. The needle loop is at this time upon the looper, and this movement of the looper will aid in the drawing of the previous stitches tight.

It will be noted that the feed dog is moved back and forth and is also raised and lowered and the looper is given a needle avoiding movement all by the single eccentric which operates the rock lever 16. It will also be noted that the looper support 19 has a cut-away portion between the sleeves 20 and 21, which allows the needle to move to the lower end of its stroke without striking the looper support.

Having thus described my invention, what I claim as new and desire to secure by Letters Patent, is:—

1. A sewing machine including in combination, a work support, a needle, a looper coöperating with said needle wholly be-

neath the work support, means for carrying said looper whereby it swings about a substantially vertical axis when moving into and out of the needle loop, and means for 5 moving said looper carrying means about a horizontal axis for swinging the looper bodily from one side of the needle to the other for its needle avoiding movement.

2. A sewing machine including in combination, a work support, a needle, a looper coöperating with said needle wholly beneath the work support, a looper carrier, means for supporting said carrier, whereby the same moves about a substantially vertical 10 axis, a looper support on which said carrier is mounted, and means for oscillating said support about a horizontal axis for moving the looper from one side of the needle to the other for its needle avoiding movement. 15

3. A sewing machine including in combination, a needle, a looper coöperating with the needle wholly beneath the work support, a looper carrier mounted to swing about a substantially vertical axis, a link connected 20 to said looper carrier for oscillating the same, a looper support, an arm carried by said looper support and having a bearing for said looper carrier, said looper support being mounted to swing upon a substantially 25 horizontal axis, and means for oscillating said looper support for carrying the looper from one side of the needle to the other for its needle avoiding movement. 30

4. A sewing machine including in combination, a needle, a needle lever having an extension, a looper, a looper carrier mounted to swing about a substantially vertical axis, a link connected to said looper carrier, a rock lever connected to said link, a second 35 link for connecting said rock lever to the needle lever extension, said link and needle lever extension being so disposed as to give an extended dwell to the looper at the forward end of its stroke, a looper support, 40 means for oscillating said looper support about a substantially horizontal axis, said 45

looper support having an arm on which said looper carrier is mounted.

5. A sewing machine including in combination, a work support, a needle, a looper 50 coöperating with said needle wholly beneath the work support, a looper carrier, means for supporting said looper carrier whereby the same moves about a substantially vertical axis, and means for moving 55 said supporting means for tilting the axis of the looper carrier relative to the path of the needle for moving the looper to the opposite side of the needle for its needle avoiding movement. 60

6. A sewing machine including in combination, a work support, a needle, a looper coöperating with the needle beneath the work support, a looper carrier, means for oscillating said looper carrier about a substantially 65 vertical axis, a looper carrier support, an arm projecting laterally from said support and pivotally supporting said carrier, said arm being substantially horizontal when said looper is moving into and out of the needle loop, and means for oscillating said looper support for moving said arm to an inclined position for carrying the looper to the opposite side of the needle for its 70 needle avoiding movement. 75

7. In a sewing machine, the combination of a feed dog, a needle, a looper, a support pivoted to swing about a horizontal axis, said support having a laterally projecting arm swinging in a vertical plane, a looper 80 carrier mounted on said arm and swinging in substantially a horizontal plane, means for swinging the looper carrier, said looper support having a connection to the feed dog located on one side of the axis of said support. 85

In testimony whereof I affix my signature, in presence of two witnesses.
